UNITED STATES PATENT OFFICE.

HENRY C. STUCKENBURG, OF LOUISVILLE, KENTUCKY, ASSIGNOR TO BRIDGEFORD AND COMPANY, OF LOUISVILLE, KENTUCKY, A CORPORATION.

GRATE.

979,719.

Specification of Letters Patent. Patented Dec. 27, 1910.

Application filed May 23, 1908. Serial No. 434,672.

To all whom it may concern:

Be it known that I, HENRY C. STUCKENBURG, a citizen of the United States, residing at Louisville, in the county of Jefferson and State of Kentucky, have invented certain new and useful Improvements in Grates, of which the following is a specification.

In order to make the invention more clearly understood I have shown in the accompanying drawings means for carrying it into practical effect, without limiting my improvements, in their useful applications, to the particular details of construction which, for the sake of example, I have illustrated.

In said drawings—Figure 1 is a front view of a grate embodying the invention. Fig. 2 is a vertical sectional view on line 2—2 of Fig. 1. Fig. 3 is a side view of a portion of the frame, showing the bearing brackets and bearing lugs. Fig. 4 is an end view of the basket. Fig. 5 is an end view of the crown. Fig. 6 is a horizontal section on line 6—6 of Fig. 3. Fig. 7 is a sectional view similar to Fig. 2, but with the crown turned up and back against the basket and with the summer front in place.

Referring to the drawings, 1 indicates the frame adapted to be arranged at the front of a fireplace. This frame is or may be of an ornamental character, having sides 2 and a top 3 connecting the sides. The parts 2, 2 and 3 are shown as cast in one piece, but they may be made separate and secured together by rivets or bolts. Each frame side is provided with a pivot bearing bracket 4 which extends rearwardly from the frame side and also laterally toward the middle of the space between the two frame sides 2. The bracket 4 has a pivot bearing 5 to be engaged by the pivot or trunnion of the basket, and a stop shoulder or surface 6 to be engaged by a portion of the basket when the latter is dumped forward and also to be engaged by the crown when the latter is tilted upward and backward. Each frame side is also provided with a pivot bearing lug 7 situated below the bracket 4, extending a little backward from the side 2 and also laterally inward to be in the path of a portion of the lower part of the basket so as to arrest the latter in its normal position.

8 indicates stops to engage the upper part of the summer front when the latter is fitted into the frame, and 9 indicates stops to en-

gage the lower part of the summer front, or to engage the lower part of the crown when the same is in normal position.

10 is the basket, which is narrower than the space between the sides 2 so as to be readily inserted between them and so as to be tilted forward between the sides to dump the contents of the basket. It is provided with pivots or trunnions 11 arranged to fit in the bearings 5 of the brackets 4, and with laterally extending stops 12 which engage the backs of the lugs 7 to sustain the basket in its vertical or normal position.

13 is a space or notch in the front 14 of the basket which enables the front to swing over the bracket 4, and 15 is a stop on the front which engages the shoulder 6 when the basket has been tilted forward into dumping position. The parts are so proportioned that the basket will remain by its own weight in this position resting against the shoulders 6.

16 is a space or notch in the front 14 which enables the lower part of the front to swing backward clear of the bracket 4.

17 is the crown arranged between the sides 2 and below and a little forward of the front 14 of the basket. It is provided with pivots or trunnions 18 which fit in the bearings of the lugs 7, so that the crown may be tilted forward and upward on a horizontal axis against the shoulders 6. The crown in its normal position occupies the space between the lower parts of the frame sides 2 which is to be occupied by the lower part of the summer front when the latter is fitted in the frame. The pivots 18 are, however, arranged out of the vertical plane of the front and to the rear of the same, as shown, so that when the crown is swung up against the shoulders 6 it will be to the rear of the plane of the summer front and permit the insertion of the latter. The front 14 of the basket is arranged sufficiently to the rear of the crown to admit of this fitting of the parts.

19 is the summer front which preferably fills the entire space between the frame parts 2, 2 and 3 so as to cover the basket and crown, the latter having been swung up as described. The top of the front 19 fits under and within the frame top 3 to hold the front from tipping forward, and it is supported from behind by the stops 8 and 9.

The brackets, lugs and pivots or trun-

nions are shown as cast integral with the frame, basket and crown, respectively, but it will be understood that they may be attached by rivets, bolts or other means.

5 The frame may be set in a masonry fireplace in a permanent manner, or it may have side, rear and top walls which inclose the basket in a known manner.

It will be understood that by tilting the 10 basket forward, as described, the contents of the basket may be dumped into an ash receptacle, placed for the purpose, in a very convenient manner. Also, that the crown may be swung upward and will so remain, 15 without removing it from the frame, to admit of clearing the ashes from below the basket.

What is claimed is—

1. In a grate the combination of a frame, 20 a basket pivotally mounted therein on a horizontal axis and arranged to be tilted forward between the sides of the frame, a crown pivotally mounted in the frame on a horizontal axis which is at the rear of the 25 crown and at a point in advance of the basket, and arranged to be tilted up and back against the front of the basket out of the vertical plane of and to the rear of a summer front, thereby leaving room for a 30 summer front, and a summer front fitting in the frame and occupying by its lower end the space normally occupied by the crown, substantially as set forth.

2. In a grate the combination of a frame 35 having at each side a pivot bearing, and having below the same a laterally extending bearing lug, a basket having at each side a pivot engaging one of the said pivot bearings and

arranged to be dumped forward, and having stop portions engaging the rear sides 40 of the said bearing lugs to hold the basket in normal position, and a crown below the basket having pivots engaging the said bearing lugs and arranged to be tilted up at the front of the basket, substantially as 45 set forth.

3. In a grate the combination of a frame, a basket pivotally mounted therein on a horizontal axis and arranged to be tilted forward between the sides of the frame, and a crown arranged to occupy the space between the sides of the frame below the basket and having rearward extensions carrying pivots 18 which are at the rear of and out of the vertical plane of the crown, and 50 bearings 7 on the frame at the front of the basket and engaging the said pivots, the crown being adapted to be tilted up against the front of the basket, substantially as 55 set forth.

4. In a grate the combination of a frame, pivot lugs 4 thereon, and a basket having pivots 11 near the front plane of the basket and held in bearings in the said lugs, and having stops 15 above the pivots arranged to swing forward and downward in front of the pivots and to engage the front of the lugs when the basket is tilted forward of the frame, substantially as set forth.

In testimony whereof I affix my signature 70 in presence of two witnesses.

HENRY C. STUCKENBURG.
